UNITED STATES PATENT OFFICE.

JOHN F. O'CONNOR, OF CHICAGO, ILLINOIS, ASSIGNOR TO WILLIAM H. MINER, OF CHAZY, NEW YORK.

SIDE BEARING FOR RAILWAY-CARS.

1,357,804.

Specification of Letters Patent.

Patented Nov. 2, 1920.

Application filed May 23, 1919. Serial No. 299,279.

To all whom it may concern:

Be it known that I, JOHN F. O'CONNOR, a citizen of the United States, residing at Chicago, in the county of Cook and State of Illinois, have invented a certain new and useful Improvement in Side Bearings for Railway-Cars, of which the following is a full, clear, concise, and exact description, reference being had to the accompanying drawings, forming a part of this specification.

My invention relates to improvements in side bearings for railway cars.

One object of my invention is to provide a simple self-centering side bearing. Other objects will appear from the description of my invention hereinafter following.

In the drawings forming a part of this specification, Figure 1 is a transverse section of the bolsters of a car showing my improved side bearing attached thereto, the side bearing being illustrated in longitudinal, vertical section and partly in end elevation. Fig. 2 is a cross-sectional view taken on line 2--2 of Fig. 1. Fig. 3 is a horizontal, sectional view taken on line 3--3 of Fig. 1. Figs. 4 and 5 illustrate modifications,--Fig. 4 showing the modified form in vertical, longitudinal section, and Fig. 5 being a cross-sectional view taken on line 5--5 of Fig. 4.

Referring to the drawings, and first describing the embodiment of my invention illustrated in Figs. 1, 2 and 3 of the drawings, the numeral 10 indicates a body bolster and 11 a truck bolster of a railway car. In the particular adaptation of my invention shown, the side bearing is secured to the truck bolster and comprises a base member 12 open at its upper end 13 and preferably open at its lower end 14 forming a substantially rectangular box provided with the lugs 15, through which are passed the riveting means 16 to secure the base member to the truck bolster 11. A base block 17 rests within the base member and upon the truck bolster the said block having a flat upper face 18 and being provided with a cored out under face as indicated at 19--19. A wear plate 20 rests upon the base block, the said plate extending at its ends into the apertures 21--21 provided in the end walls of the base member, the said wear plate being suitably perforated as at 22--22 for the passage of cotter to secure it against acci-

dental displacement. Intermediate their ends, the side walls of the base member are internally provided with the recesses 23 in which the counterweights 24 attached to the roller 25 are received.

The roller 25 is of a cylindrical form arranged with its ends adjacent the side walls of the base member and provided below its axis with the outstanding counterweights 24 which overhang the wear plate 20 and the base block 17. Their position within the recesses 23 of the base member is clearly illustrated in Fig. 2 of the drawings. Each recess 23 is provided with end walls 26--26 and the edges of the counterweight 24, as indicated at 27--27, are at the widest portion, as at 28, in close proximity to the end walls 26 of the recess 23. Below this point the edges 27 of each counterweight 24 are inwardly curved as indicated at 29--29 and above said point are inwardly turned, so that in general shape each counterweight is in end view a pentagon, as illustrated in Fig. 1 of the drawings.

By reason of the location, shape and arrangement of the counterweights, it will be observed that when the roller 25 is in its normal central position, as illustrated by the full lines in Fig. 1 of the drawings, the counterweights hang within the recesses 23, and because of the close proximity of their edges as at 28 to the ends of the recess 23, jarring or other disturbing movements will not accidentally move the roller from its central position and at right angles to the axis of the base member, but the same will be kept securely in its normal position except when it is engaged by the bearing face 30 of the opposed bolster 10. In the event of such engagement and movement of the upper bolster, for instance, to the right in respect to the lower bolster, the roller will roll upon the wear plate 20 and if not disengaged by the upper bearing plate before it has traveled its full rolling movement in one direction, will be carried to the end of the base member as indicated by the dotted lines referenced 31 in Fig. 1 of the drawings.

During this rolling movement to the right as shown in Fig. 1, the counterweight will travel upwardly and to the right, its lower left curved edge permitting the upward travel of said face adjacent the wall of the recess 23 and the upper right hand edge of

the counterweight will, because of its conformation, be permitted to travel toward the other end wall of the recess 23 until it will have assumed on the position of the roller 5 just described, the position shown by the dotted lines in Fig. 1 of the drawings and referenced 32.

By means of this construction, I have provided a simple and efficient roller side bearing which is self-centering through gravity and in which the roller is bound to assume its central position on release of pressure because of the disposition and conformation of the counterbalances 24 and the employment thereof in connection with the recesses 23 in the side walls of the base member.

In assembling this bearing, the roller is placed in its position through the lower opening of the base member and is prevented from upward passage therethrough by the top walls 33 of the recesses 23, as most clearly illustrated in Fig. 2 of the drawings. Then the wear plate 20 is placed in position through the openings 21, the base block inserted and all placed upon the bolster and secured thereto, the cotter pins serving, as will appear from Fig. 1 of the drawings, to hold the base block as well as the wear plate in their assembled position.

80 In the modification illustrated in Figs. 4 and 5 of the drawings, I employ the same principle with a somewhat different construction. It will be understood that the side bearing is mounted similarly to that illustrated in Figs. 1, 2 and 3 of the drawings and that it performs the same functions.

Referring to Figs. 4 and 5, the numeral 40 indicates a base member open at the top 40 and partially closed at the bottom by the bottom members 41—41 upon whose upper faces are arranged the wear plates 42—42 secured against accidental displacement from the base member by the cotters 43—43. 45 The members 41 and the wear plates 42 are spaced apart forming between them a groove or way 44 within which the counterweight 45 of the roller 46 depends.

The roller 46 is provided at its ends with 50 the pins 47 which extend into the recesses 48—48 with which the side walls of the base member are provided, the said pins being insertible and removable in one position of the roller through the openings 49—49 formed in the said side walls. The said roller 46 is of general cylindrical shape with a central portion on either side thereof cut away in the general form of a V-shaped recess as indicated at 50—50, the remaining 55 lower central portion of the roller by reason of this cutting away forming with the counterweight 45 a pentagonal-shaped member very similar in shape and function to the member 24 shown in Fig. 1 of the drawings.

60 The recess within which this member is

received is formed by the groove 44 which is terminated at either end by the walls 51—51 which are extended upwardly beyond the plane of the wear plates and then outwardly horizontally extended as indicated by the numerals 52—52 in Fig. 4 of the drawings, so that in normal position of the parts, the roller is centrally disposed with the counterweight depending in the recess 44, the walls 51—51 of the recess serving to prevent the accidental bodily displacement of the roller from its central position and the edges of the counterweight and the extension thereof into the roller being so conformed as to permit the rolling 80 of the roller in either direction.

On movement of the roller, as for instance, when moved to the right hand end of the base member, it will assume the position indicated by the dotted lines in Fig. 4, referenced 53, and the counterweight will assume the position indicated by the dotted lines in said figure, referenced 54. The upper edge of the V-shaped groove on the side toward which the roller rolls, as for instance, the face 55, will engage the face 51 of the horizontal wall hereinbefore described, such engagement being simultaneous with the engagement of the roller against the end wall of the base member, thus limiting its endwise movement and permitting the use of a counterweight of such position and weight to positively return the roller to its normal central position and to require it to register by reason of the necessity of the registration of the counterweight within the recess 44 hereinbefore described.

It will be obvious that the principle of my invention may be variously embodied and by illustrating only two embodiments thereof, I do not intend to limit myself to these special forms. Also in the claims herein-after following, it will be obvious that the wear plate which is included as an element in some of the claims may be a separate member as illustrated in the figures of the drawings or may be a part of the base member or of a bolster or may be anything upon which the roller is designed to roll.

I attach particular importance to the form and functions of the counterweights 24 and 45 of the two forms illustrated. Amplifying somewhat the description heretofore given of these parts, I may add that the contour of the edges 29—29 of the form shown in Fig. 1 and the corresponding edges of the other modification, are so designed that, as the roller 25 rolls bodily to either side of normal, the space or distance between the corresponding edge 29 and the adjacent vertical wall 26 of the base casting will remain substantially constant and without binding. Stated in another manner, the horizontal distance across the counterweights 24 in any position of the roller will always approach 130

- the width of the guideways within which said counterweights travel. In this manner, it is impossible for the roller to be bodily shifted at any time or to come to rest at any place except its normal position when free from load. The counterweights therefore perform a double function in that they assist the return of the roller to normal position under the influence of gravity and also 5 maintain the proper relation between the roller and the base casting or retaining member 12 at all times. By having the side walls of the guideways 23 extend vertically and the contours of the counterweights 24 correspondingly formed, it is impossible for the counterweights to ever lodge upon any projection or shelf, even accidentally, thus insuring the return of the roller to normal 10 at all times and under all conditions.
- 10 I claim:
1. In a side bearing for railway cars, in combination: a base member, a wear plate therein, a roller mounted on the wear plate, a pentagonal counterweight attached to said roller, the base member having a recess to receive said counterweight.
  2. In an anti-friction bearing of the character described, the combination with a retaining member adapted to be held in place 15 on a bolster or the like, said retaining member being provided with a horizontally extending flat bearing surface; of a roller retained within said member and adapted for bodily rolling to each side of normal position 20 on said bearing surface, said retaining member having a centering guideway therein defined by a pair of horizontally spaced, vertically extending parallel sides; and a combined centering and overbalancing, radially extending element rigid with respect to the roller and normally depending vertically, said centering and overbalancing element being disposed and confined within said guideway during all movements of the roller 25 and adapted to be elevated within said guideway when the roller is moved to either side of normal, the contour of the edges of said centering and overbalancing element being so formed that said element is free to move 30 within said guideway during rolling movement of the roller and at the same time the maximum dimension through said element, in any position thereof, taken horizontally and perpendicularly to said vertical sides in 35 a direction transverse to the axis of the roller, will substantially approximate the width, in the same direction, of the guideway, thereby preventing any bodily displacement of the roller.
  3. In an anti-friction bearing of the character described, the combination with a hollow substantially rectangular retaining member, the inner faces of the opposed side walls 40 of said member being provided with guide recesses therein; of an anti-friction roller 65 disposed within said retaining member, said roller being provided at each end thereof with a combined centering and over-balancing section rigid with respect thereto, said sections coöperating with said guide recesses to prevent bodily shifting of the roller while at the same time permitting rolling movement thereof to either side of normal position.
  4. In an anti-friction bearing of the character described, the combination with a hollow substantially rectangular retaining member, the inner faces of the opposed side walls of said member being provided with guide recesses therein; of an anti-friction 70 roller disposed within said retaining member, said roller being provided at each end thereof with a combined centering and over-balancing section rigid with respect thereto, said sections coöperating with said guide recesses to prevent bodily shifting of the roller while at the same time permitting rolling movement thereof to either side of normal position.
  5. In an anti-friction bearing of the character described, the combination with a hollow substantially rectangular retaining member having vertically extending guide 75 recesses on the inner faces of the opposed side walls thereof; of a separable base block disposed within said retaining member; and an anti-friction roller within said retaining member, the weight of which is adapted to 80 be sustained by said base block, said roller having combined centering and over-balancing sections rigid with respect thereto at each end thereof and coöperating with said guide recesses.
  6. In an anti-friction bearing of the character described, the combination with a hollow substantially rectangular base casting having the opposed inner surfaces of the side walls thereof provided with guide recesses, 85 the sides of which extend vertically; of a base block disposed within said retaining member and separable therefrom; a bearing plate mounted within said retaining member and extending horizontally along 90 the top of said base block; and an anti-friction roller within the retaining member adapted to roll on said plate, said roller having combined over-balancing and centering sections integrally formed therewith at each 95 end thereof and coöperable with said guide recesses.

In witness that I claim the foregoing I have hereunto subscribed my name this 19th day of May, 1919.

JOHN F. O'CONNOR.
